Primary Examiner — Karen S Acker*Assistant Examiner* — Jerry Shiuan-Hua Hsu(74) *Attorney, Agent, or Firm* — Vierra Magen Marcus LLP(57) **CLAIM**

The ornamental design for a headrest attachment element, as shown and described.

DESCRIPTION

FIG. 1 is a front perspective view of a headrest attachment element, showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The claimed design is intended to be used to attach an item to posts of a headrest.

The broken lines illustrate environmental matter that forms no part of the claimed design.

1 Claim, 8 Drawing Sheets(56)
